UNITED STATES PATENT OFFICE.

WILLIAM P. DAY, OF CLEVELAND, OHIO.

RENEWABLE RAIL-BED STRUCTURE AND METHOD OF CONSTRUCTION.

Application filed May 10, 1924. Serial No. 712,208.

To all whom it may concern:

Be it known that I, WILLIAM P. DAY, a citizen of the United States, residing at Cleveland, in the county of Cuyahoga and State of Ohio, have invented certain new and useful Improvements in Renewable Rail-Bed Structures and Methods of Construction, of which the following is a specification.

10 This invention relates to the construction of rail beds and particularly to the method of forming a substructure or bed beneath the rails of street railway tracks and to the structure itself.

15 Ordinarily in the construction of beds for street railways, the concrete is tamped under and around the steel ties to make certain of a complete bearing. There is always more or less difficulty attendant 20 upon this method as it is difficult to get the workmen to tamp the concrete to make certain of a complete and uniform bearing, unless the operation of the mixing of the concrete is followed very closely by continuous inspection. The workmen will be 25 inclined to make the mix too soft in order to make it flow under the plates easily, thus reducing their labor in tamping it, and this use of a relatively soft mix reduces 30 the strength of the concrete.

Another difficulty encountered where concrete is used as a road bed immediately beneath the rails and metallic tie structure of the road, is that when it is required to 35 renew the rails, it is necessary to dig up this concrete which is a difficult operation, in order to put down the new rails.

One of the objects of the present invention is to provide a substructure for street 40 railway rails and to provide a method of forming this substructure such that this difficulty of tamping the concrete will be entirely obviated, and further to so form this substructure that the middle portions 45 of the ties between the tracks are embedded or otherwise engaged with the concrete base of the road bed but that the supporting or bearing plates and the rails themselves are initially left in spaced relation to the concrete base, this space being afterwards filled in by tamping with a dry mix or with any suitable material which will form a

supporting layer for the bearing plates and for the rails themselves between the concrete and the bearing plates and rails which 55 also, after it sets, may be removed to permit the removal and the renewal of the rails without cutting into or in any way affecting the original concrete base, so that after the new rails are set in place and, if necessary, new supporting plates or bearing 60 plates are put in place, a fresh layer of filling material, preferably of a cementitious nature, may be tamped beneath the bearing plates and beneath the rails, thus 65 rendering the renewal of the rails a relatively cheap and easy matter as against the relatively difficult and expensive matter under the old arrangement.

A further object of the invention is to 70 provide a filling layer of a different character or type than the concrete base, this layer being softer than the concrete base and of such a different character that a clear line of demarcation or cleavage is 75 secured between the filling layer and the concrete base, making it a comparatively easy matter to remove the filler from under the rails and plates when the renewal takes 80 place.

Another object is to provide a method of construction which locks the track down to the road bed before the tamping of material beneath the rails and beneath the bearing plates takes place, so that when the 85 filling is tamped beneath the rails and beneath the bearing plates, this tamping operation will not act to tilt or otherwise get the track structure out of proper horizontal position or the position in which it is desired 90 to be, this tamping of the filling material under these circumstances beneath the rails and bearing plates acting to lock the track and make a particularly effective track supporting structure.

Still another object is to provide a method of construction which insures a much more rigid type of track foundation than is possible with the ordinary methods 95 of construction.

With these and other objects in view, as will more fully appear as the description proceeds, the invention consists in the method and apparatus hereinafter described 100

and claimed, and illustrated in the accompanying drawings, wherein:

Figure 1 is a plan view of a track structure showing the first step in my improved method;

Fig. 2 is a longitudinal section showing the second step in my improved method;

Fig. 3 is a longitudinal section showing the third step in the method;

Fig. 4 is a like view to Figure 3 but showing the fourth step;

Figure 5 is a like view to Figure 4 but showing the last and final step in carrying out my invention;

Figure 6 is a section on the line 6--6 of Figure 4;

Figure 7 is a section on the line 7--7 of Figure 5;

Figure 8 is a cross sectional view on the same plane as Figure 6, but showing a slightly modified form of construction;

Figure 9 is a like section to Figure 8 but showing the filler and the sealing concrete in place.

Referring particularly to Figures 1 to 4, which illustrate step by step the construction of the track, it will be seen that I have illustrated the rails A as being immediately supported by means of a tie structure such as illustrated in my Patent #1,317,779, granted on the 7th day of October, 1919, this tie structure comprising bearing plates 10 upon which the rails rest and transverse ties or bars 11 extending between and attached to the bearing plates and thus holding the bearing plates, and therefore the rails, from any movement out of parallelism. The members 11 are preferably angular in cross section, as illustrated in Figure 2. The plates 10 are formed to provide for rail clamps 12 and bolts 13 which hold the rails A down upon these supporting or bearing plates 10.

It is usual in laying a track comprising the rails A and the plates 10 and transverse members 11 to form a concrete base entirely beneath the track and extending laterally outward beyond the plates 10, this concrete base extending longitudinally along the entire track. In carrying out my method of making the rail bed, I first dispose the rails upon blocks 14, as illustrated in Figure 2, these blocks resting upon the sub-base 15 of the road bed, these rails having attached thereto the plates 10 and the transverse ties or members 11. After the rails have been placed in the position which they are to occupy and supported upon the blocks 14, I fill the space between the sub-base 15 and the rails A with concrete 16 (see Fig. 3). This concrete is preferably filled up to a level with the under faces of the plates 10 and slightly above the upper faces of the transverse members or tie bars 11, as illustrated in Fig. 6, thus embedding the mem-

bers or tie bars 11 and holding these members from upward movement. Before this concrete is set, a depth of about two inches is removed from beneath the rail and beneath the bottom of the plates 10 (see Fig. 4), this concrete beneath the plates 10 being removed for a distance on each side of the plates and the same being true with regard to the rails, this distance being sufficient to permit a dry mix or other filler to be tamped into place beneath the rails and beneath the plates 10. Attention is called to the fact that the concrete extends over the cross ties or tie members 11 so that these tie members between the plates are firmly engaged with the concrete base 16.

After the concrete has set and thoroughly hardened, the space 17 beneath the plates 10 and beneath the rails A, as shown in Figure 5, is tamped with a filling 18. This is preferably a dry mix, though I do not wish to be limited to this, and preferably is cementitious in character. This dry mix may be, for instance, composed of asphalt or may be a dry mix of slag screenings and cement or any other material. At any rate, it should be a mix of asphalt or a preparation of asphalt and some other material which is softer than the concrete and which will be of such a different character that there will be a distinct plane of cleavage between the filler and the concrete after the filler has hardened and which will be easier to remove from under the rails and plates when renewal takes place. This also gives the cars a chance to ride on the tamped material rather than on the original base of concrete. Preferably this tamping is done with power tampers and after this filler is fully set the rails are then disposed upon the plates 10 and held down by the bolts and fastening devices.

There is a difference between the concrete and the filler and a distinct line of demarcation between the two which permits the filler to be cut away from beneath the rail and from beneath the tie plate 10 whenever it is desired to remove the original rail and renew it. The renewal of the rails is thus rendered much cheaper than it would otherwise be for the reason that the concrete base does not have to be cut into and more or less destroyed in order to remove the rails, and all that has to be destroyed or removed is the relatively softer filling 17 between the concrete base and the under faces of the plates.

Furthermore, when the filler 17 is tamped between the base and the plate 10 and between the base and the rail, this filler as it is forced inward forces the plate and the rail upward because the middle portions of the ties or the transverse members 11 are held firmly against any upward movement and against any movement in either

direction by being embedded in the concrete. Thus there is no danger of the tie structure getting out of place or lifting more on one side than the other. If these ties or transverse members were not held down at the middle by the cement or concrete and a dry mix was then tamped beneath the rails and beneath the rail supporting plates, there would be a tendency for one workman to tamp more material beneath the bearing plate and beneath the rail than another workman and thus this would cause the track to be out of level in spots. Where the middle portion of the track structure, that is the transverse members 11, are positively held down by the concrete, it is obvious that no amount of tamping beneath the bearing plates or beneath the rails will shift the rail structure out of its proper position.

In Figures 8 and 9, I illustrate a construction wherein after the filler 18 is put in place and tamped between the bottom of the recess 17 and the under face of the plate 10 and the rail A, a sealing mass of concrete, designated 19, is used to fill up the recess 17 and to extend over the top of the plate 10, the fastening devices, and the base of the rail A. This sealing mass 19 of concrete, after it has set, holds the filling in place, prevents its removal, and at the same time acts to hold the rails firmly in place upon the substructure. At the same time this sealing mass of concrete is not bonded to the concrete 16 so that the sealing mass of concrete 19 may be readily removed and the filler removed when it is desired to replace or renew the rails. It will be seen that this construction is the same in principle as the construction which I have heretofore described, except that the filler is entirely sealed in and protected by the sealing mass 19.

While this new method of concreting the ties under the bearing plates, that is of placing filling material beneath the bearing plates, is slightly more expensive than the old construction, the assurance of having a complete bearing more than justifies this added cost, and not only is there this assurance, but there is an assurance that the track will not be thrown out of level and that the renewals may be made at a much less cost than ordinarily, and it will be noted that these renewals do not require the destruction or non-use of the original concrete base but that this concrete base is used as a support for the original filling and for the filling which will be placed beneath the renewed rails and plates if the plates 10 are renewed. While I preferably use a cementitious filler 18 beneath the plates 10 and the rails, I do not wish to be limited to a cementitious filler as a filler of any other character might be used.

I claim:—

1. A method of forming a railroad bed including blocking up the parallel rails of the track and connecting the rails by transverse members, casting concrete beneath the rails and transverse members, this concrete being engaged with the transverse members, but there being a space formed between the under faces of the bases of the rails and the concrete, allowing the concrete to set, and filling the space between the rails and the concrete with a filling of softer character than the concrete. 70

2. A method of forming a bed for railroad track including connecting the parallel rails of the track by transverse members and supporting plates at intervals beneath the rails, forming a concrete base extending transversely and longitudinally beneath both rails and beneath said plates, the transverse members being embedded in the concrete, forming a space between the concrete and the under faces of the rails and the under faces of the supporting plates, allowing the concrete to set, and filling the said space with a filler. 80

3. A method of forming a bed for railroad track including connecting the parallel rails of the track by transverse members and supporting plates at intervals beneath the rails forming a concrete base extending transversely and longitudinally beneath both rails and beneath said plates, the transverse member being embedded in the concrete, forming a space between the concrete and the under faces of the rails and the under faces of the supporting plates, allowing the concrete to set, and filling the said space with a cementitious filler having a different character from the concrete. 100

4. A method of forming a railroad track bed including connecting the parallel rails by bearing plates disposed at intervals beneath the rails and by transverse tie members connected to the bearing plates, supporting the parallel rails and the plates and ties in spaced relation to the said bed, filling the space between said rails, the transverse members, the plates and the said bed with concrete, said concrete extending on each side beyond the rails and longitudinally for the entire length of the track, the transverse members between the plates being fully engaged with the concrete, allowing the concrete to set and while it is in a partially softened condition cutting out the concrete from beneath the rails and beneath said plates, tamping a cementitious filler between the plates and the concrete base and between the plates and the concrete base, and allowing the cementitious filler to harden, the cementitious filler being of such character that a line of demarcation is left between the filler and the concrete base. 110

5. A method of forming a bed for rail- 130

road rails comprising casting a concrete base beneath the rails, allowing the concrete to set, cutting the concrete base out from beneath the rails to a width greater than the width of the rails, and filling the space between the concrete and the rails with a cementitious filler having a character softer than that of the concrete base whereby said filler may be cut out without cutting into the concrete base.

6. A method of forming a bed for railway rails and bearing plates upon which the rails rest consisting in forming a concrete base beneath the rails and bearing plates, allowing said concrete base to set, cutting the concrete base while still slightly soft from beneath the rails and the plates, tamping the space between the concrete base and the rails and plates with a cementitious filler, and forming curbs on each side of the rail and the plate to prevent the lateral spreading of the filler.

7. A rail supporting structure comprising rail supporting plates, rails mounted upon the supporting plates, transverse ties connecting the plates, a base of concrete embedding the transverse ties and extending beyond the rails on each side thereof and longitudinally along the track, the concrete base being formed to provide a space beneath the under faces of the rails and the plates, and a filling of cementitious material, relatively softer than the concrete base, disposed between the under faces of the plates and the under faces of the rails and the upper face of the concrete base and having a width greater than that of the plates and of the rails.

8. A rail supporting structure of the character described comprising parallel rails, bearing plates disposed at intervals along the track and upon which the rails immediately rest, transverse tie members connected to said bearing plates and extending

transversely between the rails and base of concrete disposed beneath the rails, the plates, and embedding the transverse ties, the base beneath the plates and rails being reduced in thickness so as to provide a space between the upper face of the base and the plates and rails and of a width greater than that of the plates and rails, and a filling of cementitious material tamped into place in this space and having tight contact with the walls of the space and with the under faces of the plates and rails, this filling being of a cementitious nature but of a different and relatively softer character from the character of the base.

9. A rail supporting structure of the character described comprising a concrete base, a rail supported in spaced relation to the concrete base, and a filler of cementitious material disposed between the rail and the base having a width greater than that of the rail and tamped beneath the rail, there being a clear plane of demarcation between the filler and the concrete base, the filler being of material which may be more readily removed than the concrete of the base.

10. A method of forming a bed for railroad track including connecting the parallel rails of the track by transverse members, forming a concrete base extending longitudinally and transversely beneath the rails and transverse members, the transverse members being embedded in the concrete, forming a space between the concrete and the under faces of the ends of the transverse members, said space extending beyond the transverse members and being wider than the width of the rail allowing the concrete to set, and filling said space with a cementitious filler.

In testimony whereof I affix my signature.

WILLIAM P. DAY.
